UNITED STATES PATENT OFFICE.

CHARLES PELISSIER, OF CONCORD, NEW HAMPSHIRE, ASSIGNOR OF ONE-HALF TO GEORGE H. EMERY, OF SAME PLACE.

MACHINE FOR FORMING AND STAMPING LOOPS.

SPECIFICATION forming part of Letters Patent No. 296,050, dated April 1, 1884.

Application filed February 8, 1884. (No model.)

To all whom it may concern:

Be it known that I, CHARLES PELISSIER, a citizen of the United States, residing at Concord, in the county of Merrimac and State of New Hampshire, have invented a certain new, useful, and Improved Machine for Forming and Stamping Loops for Harnesses, of which the following is a specification.

The object of my invention is to bring a loop into the required shape by the dies which impress the desired figure or design upon its top and sides, and also by the same operation to square the ends of said loop so perfectly as to leave every loop in a finished state when taken from the machine.

My improved machine consists of a suitable press, which may be so constructed as to be operated either by hand or power, having a screw placed vertically with the bed exerting a pressure downward upon the strap to which a loop is sewed, and two screws placed at either end operating horizontally toward the center of said bed, which, when set in motion by suitable gearing, force both side and end dies upon the loop simultaneously, the said bed, upon which the dies or stamps and the loop are placed, being heated by gas or otherwise while the machine is in use.

Reference may be had to the accompanying drawings, forming part of this specification, in which similar letters of reference indicate corresponding parts in all the figures, of which—

Figure 1 represents a front elevation of my machine having stamping-die plates removed, Fig. 2 being a sectional plan at Y Y, Fig. 1, having stamping-die plates in position ready for use. Fig. 3 is a longitudinal sectional elevation of the iron bed. Fig. 4 is a detail view of the die which makes the impression upon the top side of a loop. Fig. 5 is a detail view of one of the dies used upon the side of a loop. Fig. 6 is a detail view of an end block, by the use of which the ends of a loop are given a square finish. Fig. 7 represents a loop as when in position to be stamped, resting within or upon the parts shown in Figs. 4, 5, and 6. Fig. 8 represents a plan view of the hand-lever as when in position upon the vertical screw.

The press may be formed either of iron or wood, or both. The drawings represent one as constructed of cast-iron.

The bed A of the press is formed substantially as shown in Fig. 3, having at equal distances from either end thereof the cavity a, for the reception of the blocks B, into which suitable nuts, C, to which the horizontal screw-shafts D are threaded, are rigidly fastened.

Upon the blocks B are placed the columns E, supporting the cap-piece F, all of these parts being held in place upon the bed A by suitable bolts and nuts, lettered, respectively, G g.

The vertical screw-shaft H may be threaded to the cap-piece F, or to a nut, I, which may enter the bottom of said piece F, and part way through the same, the latter construction being shown by dotted lines in Fig. 1. If said screw-shaft be operated by hand, a suitable double-ended lever, J, is fitted to its upper end, having a certain amount of slack; or, in other words, said lever will be so fitted to said screw-shaft as to render it capable of a certain amount of rotary motion previous to the statical moment, thus enabling an operator to accumulate for the lever J considerable force before it is applied to the screw-shaft H.

Swiveled to the screw-shaft H is a follower, K, which is guided in its movement to and away from a loop by the tongues e, projecting from the columns E, and thus prevented from any lateral play; and in order that said follower may be at all times parallel with the bed A, suitable guide-rods, L, may be secured to the follower K and pass upward and into the cap-piece F.

The screw-shafts D are provided one with a right and the other with a left thread, by reason of which said screw-shafts may be operated to and from each other simultaneously. To that portion of the said screw-shafts which is left without a thread are splined the spur-gears M M, which are prevented from any end motion by being placed between the outer bearings, N N, supporting said screw-shafts D, and the stands O O, which are bolted to the top of the bed A. By this construction the screw-shafts D are permitted the necessary end motion within the gears M M and the bearings N N while being rotated by the said gears M M and the pinions P P, which mesh with each other. The pinions P P are carried upon a suitable shaft, Q, hung in bearings R R, upon one end of which belt-pulleys may be applied;

or, if desired to operate said machine by hand, a crank may be placed thereon and answer every purpose.

A flame of gas or kerosene may be introduced into the chamber A' of the bed A, and a transverse slot, a', is cut in the top of said bed, the center of said slot being connected with the chamber A' by a small hole, a², which serves as an air-vent, and thus conducts the

10 heat from said chamber along the bottom surface of the bed-die T for its entire length; or a slot may be cut in the bottom of the bed-die T and the slot a' dispensed with, as shown in

15 Fig. 4. The top surface of said bed-die is tenoned at either end, and the length of the top surface, minus the said tenons, is equal to the length of the side die-plates, U.

The end blocks, V, are provided with a transverse slot, v, upon their top sides, and another

20 slot, v', cut in their bottom, directly underneath said slot v. The side of the end blocks, V, which comes in contact with the side die-plates, U, should be planed perfectly flat, the opposite sides being chamfered off toward either end,

25 for a purpose to be hereinafter described. The screw-shafts D act against suitable blocks, W, which present a flat surface to the side die-plates, U, (see Fig. 2,) and to either side of

30 which are attached strong lever-springs X, which spend their force upon the end blocks, V, and by reason of the chamfered sides of said end blocks the pressure of the springs X is increased with the increase of pressure obtained by the screws D. If found desirable, the screws

35 D, blocks W, and the side die-plates, U, may be so connected together as that the said screws D will draw or spread the die-plates U apart, as well as force them together; and, for the purpose of saving time while operating the ma-

40 chine, it is probably preferable so to do. The width of the tenons on the ends of the bed-die T should be such as to fit rather snug in the slot v' of the end blocks, V, and their thickness may be equally snug fit, or they may be left a

45 little loose, and the spiral springs t be so placed in holes formed in their tops, as in Fig. 4, as to slightly elevate the end blocks, V, and thus enable an operator to judge by feeling as well as by sight whether the loop is in its proper

50 place and ready to receive the pressure. This will be better understood when I say that the parts to be operated upon are placed loop-side down, and the slots v in the tops of the end blocks, V, are made narrower than the

55 width of the loop to be finished by at least the thickness of the stock of which it is composed. The thickness of the bed-die T is also less by at least the thickness of the stock of a loop than is the bottom of the slot v from the bed

60 A of the press, by which construction the ends of a loop may be squared and given equally as good a finish as are the sides and top. The surfaces of the dies T U which come in contact with a loop may be engraved in any or-

65 namental design wished. Suitable pressure-blocks will be formed of steel or iron, and attached in some convenient manner to the fol-

lower K, different widths, lengths, and forms being required for various loops. By the use of a horizontal screw at either side of a loop 70 to be finished, said loop may remain at all times in the center of the bed A, and thus be directly over the heat which passes from the chamber A' into the hole a², and thence, by means of the slot a', under the bed-die T, from 75 which it escapes, and it is obvious that the screws D may be operated by means of a crank or hand wheel upon their outer ends; but I consider the gearing shown in the drawings to be preferable.

The construction of the dies T and U and the end blocks, V, may vary somewhat from that shown in the drawings—for instance, the tenons on the die T and the slots v' in the end blocks, V, may be dispensed with and yet accomplish very good results. The side die-plates, U, may also have a flange along their sides at the bottom, as shown by dotted lines in Fig. 5, and the bed-die T, by being made thinner, may rest upon said flange instead of 80 resting upon the bed A. When a loop is ready to be formed and stamped, the side die-plates, U, should be spread apart or a little away from the bed-die T. This releases the pressure of the springs X upon the end blocks, 85 V, and a loop may then be placed in position, as shown in Fig. 7. The die-plates U and end blocks, V, should then be brought, by means of the screws D, just in contact with the loop, and the pressure first applied by the screw 90 H, after which the required pressure to complete and finish said loop may be applied by the screws D.

Having fully described my invention, what I claim as new, and desire to secure by Letters 105 Patent of the United States, is—

1. In a press constructed substantially as described, having a vertical screw-shaft, H, follower K, and bed A, the chamber A', air-vent a², and transverse slot a', as and for the 110 purpose specified.

2. In a press constructed substantially as described, having a vertical screw-shaft, H, the horizontal screw-shafts D, rotated simultaneously by means of the gears M M, pinions P P, and shaft Q, operating in the manner and for the purpose set forth.

3. In a press having a vertical screw, H, follower K, and horizontal screw D, the combination of the die-plates T U, and blocks W, with the screws D, all constructed and operating substantially as described, and for the 120 purpose set forth.

4. In a press having a vertical screw, H, follower K, and horizontal screw D, the combination of the dies T U, end blocks, V, and blocks W, having springs X, all constructed and operating substantially in the manner and for the purpose set forth.

CHARLES PELISSIER.
